(57) **CLAIM**

We claim the ornamental design for a beverage container, as
shown and described.

DESCRIPTION

FIG. 1 is a front perspective view of a beverage container
that is a first embodiment of the present invention.

FIG. 2 is a front view of the beverage container of FIG. 1.
FIG. 3 is a rear view of the beverage container of FIG. 1.
FIG. 4 is a left side view of the beverage container of FIG.
1.

FIG. 5 is a right side view of the beverage container of FIG.
1.

FIG. 6 is a top view of the beverage container of FIG. 1.
FIG. 7 is a bottom view of the beverage container of FIG. 1.
FIG. 8 is a front perspective view of a beverage container
that is a second embodiment of the present invention.

FIG. 9 is a front view of the beverage container of FIG. 8.
FIG. 10 is a rear view of the beverage container of FIG. 8.
FIG. 11 is a left side view of the beverage container of FIG.
8.

FIG. 12 is a right side view of the beverage container of FIG.
8.

FIG. 13 is a top view of the beverage container of FIG. 8.
FIG. 14 is a bottom view of the beverage container of FIG.
8.

FIG. 15 is a front perspective view of a beverage container
that is a third embodiment of the present invention.

FIG. 16 is a front view of the beverage container of FIG. 15.
FIG. 17 is a rear view of the beverage container of FIG. 15.
FIG. 18 is a left side view of the beverage container of FIG.
15.

FIG. 19 is a right side view of the beverage container of FIG.
15.

FIG. 20 is a top view of the beverage container of FIG. 15;
and,

FIG. 21 is a bottom view of the beverage container of FIG.
15.

The portions of the drawings shown in broken lines form no
part of the claimed design.
